(57) **CLAIM**

The ornamental design for a receptacle connector, as shown and described.

DESCRIPTION

FIG. 1 is a top, front and right side perspective view of a connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, rear and left side perspective view thereof; and,

FIG. 9 is a third perspective view of the receptacle connector. The broken line portion in the figure drawings is included to show unclaimed subject matter only and forms no part of the claimed design.
